UNITED STATES PATENT OFFICE.

HARRY O. DAVIDSON, OF CLEVELAND, OHIO, ASSIGNOR TO THE HYDRAULIC PRESSED STEEL COMPANY, OF CLEVELAND, OHIO, A CORPORATION OF OHIO.

CONCRETE-FORM.

1,319,048.

Specification of Letters Patent. Patented Oct. 21, 1919.

Application filed January 6, 1916. Serial No. 70,568.

To all whom it may concern:

Be it known that I, HARRY O. DAVIDSON, a citizen of the United States, residing at Cleveland, in the county of Cuyahoga and 5 State of Ohio, have invented a certain new and useful Improvement in Concrete-Forms, of which the following is a full, clear, and exact description, reference being had to the accompanying drawings.

10 This invention relates to forms or molds for the erection or construction of concrete or cement walls, and has for its general object to provide new and improved means for conveniently moving the form as the erecting 15 or building of the wall proceeds, in order to allow such erection or building to be performed as a substantially continuous operation.

In the drawings forming part hereof and 20 illustrating the present preferred embodiment of my invention, Figure 1 represents a plan view, with certain parts broken away, of a cylindrical form having my invention applied thereto; Fig. 2 an enlarged vertical 25 sectional view corresponding substantially to the line 2—2 of Fig. 1; Fig. 3 a perspective view of one of the yokes whereby the form may be moved; and Fig. 4 a similar view of one of the nuts by means of which 30 the form may be elevated.

The form illustrated herein comprises generally a plurality of hollow upright posts or ribs which form a support for the side edges of the inner plates of the form, there 35 being means associated with such uprights for clamping the plates thereto; also a plurality of plates which may be connected to form the outer shell of the form or mold, there being horizontally extending ribs or 40 liners which connect the upright posts or ribs. While the form which is illustrated herein is a circular or cylindrical form, it will be understood that the particular shape chosen for the drawings is merely illustrative 45 and that it is contemplated that my invention will be used with other shapes of forms or molds.

Describing by reference characters the various parts illustrated in the drawings, A 50 denotes generally a plurality of upright posts or ribs which support the inner plates of the form, indicated generally at B. These upright posts are connected by means of liners C, said liners being made each of a

plurality of curved segments which are 55 adapted to telescope at their ends. The outer shell of the form or mold comprises a plurality of curved plates D which are provided with means whereby they may be united at their lateral edges to form a wall 60 spaced from and surrounding the corresponding inner wall B. A convenient manner of so uniting the plates is afforded by means of angle irons d carried by the vertical edges of the plates, said angle irons 65 being riveted together, as shown at d'.

As illustrated herein, each post A is substantially channel-shaped in section and comprises a flat web 1 having divergent channeled sides 2 terminating in out-turned 70 flanges 3 which are adapted to fit within flanges 4 on Z-shaped plates secured to the vertical lateral edges of the inner plates B, whereby the inner plates of the form or mold may have a sliding engagement with 75 the posts or ribs. The posts are each preferably made of a plurality of vertical sections or lengths, which sections or lengths may be connected to form a post or rib of any desired length. As shown herein, the bottom 80 of each post or section is reduced, as indicated at a, whereby it may fit within the top of the subjacent section or length. The joints between the sections may be strengthened by means of channels 5 which are applied to the overlapping portions of the post sections and are connected thereto as by means of a strap 6 extending through aligned slots in the post sections and in the channel 85 5, each strap having a foot 7 which is adapted to bear against the inner wall of the web 1 of its post. The inner portion of each strap 6 projects through a slot in a substantially U-shaped clamp 8 the legs whereof 90 engage the opposite sides of the channel 5, 95 the clamps being secured in place by means of wedge keys 9. The particular manner in which the post sections are united forms no part of the invention in this case, the same being shown, described, and claimed in my 100 application No. 20,061 filed April 8, 1915.

As a means for clamping the inner plates of the form or mold to the posts or ribs I have shown substantially the same construction as is employed for securing the channels 105 5 to the overlapping post sections, said means comprising a number of U-shaped clamps 11 each of which is applied to a post or rib A in

substantially the same manner as the clamps 8 and which engage the lateral edges of the plates adjacent thereto, the clamps being secured in place by means of straps 12 and 5 wedge keys 13 similar respectively to the straps 6 and keys 9. The posts A also form a convenient means for supporting the platforms for the workmen, the platforms (indicated at 14) being supported by brackets 10 each comprising a horizontal support 15 for the platform and inclined braces 16 and 17, the parts 15 and 16 being detachably connected to the posts in any approved manner—as for instance in the manner disclosed 15 in my copending application referred to hereinbefore. For the purpose of lifting the mold or form, as the work progresses, in a particularly convenient manner, I provide the following construction:—

20 Certain of the vertical ribs or posts are connected by braces with the ribs or posts opposed diametrically thereto. In the drawing, all of the posts are shown as so connected. Each brace comprises a trans- 25 verse tie member 18 and each of these tie members has suitably connected to the opposite ends thereof a supporting member 19 which is shown as provided with a post or tenon 20 adapted to socket within the top 30 of one of the hollow posts A. The outer end of each member 19 projects beyond its adjacent post and forms a support for the means whereby the form is to be elevated. The member 19 may be a casting, as indicated 35 in the drawings, and may be connected to the tie member 18 in any approved manner; in the drawings the tie members are shown as projecting into and secured to sockets carried by the members 19. Each 40 member 19 is provided at its outer end with an aperture which may be formed in a sleeve 21, said sleeve having a seat 21^a at its upper side for the adjusting nut (to be described hereinafter). Through this sleeve 45 there extends a long threaded bolt 22 having a hook 23 at its lower end. 24 denotes generally a yoke which is attached to the upper ends of the inner and outer mold plates and which forms a connection whereby these 50 plates are transversely spaced and whereby they may be lifted as the erection of the wall progresses with the lateral edges of the adjacent inner plates spaced apart approximately the width of the work-facing side 55 of a post. A convenient form of the yoke is shown in detail in Fig. 3 and comprises a central bridge member 25 having attached to opposite ends thereof inverted U-shaped hangers 26. The bridge 25 is of 60 sufficient length to enable the hangers 26 to clear the Z-plates 4. The hangers may be made of channelled metal, as shown, and are riveted or otherwise suitably connected through their webbed portions to the tops 65 of the inner and outer mold plates. The

bridge 25 has formed therewith a hollow central post 27 which receives the shank 28 of a hook 29.

Reference has been made hereinbefore to the seat 21^a. This seat supports a nut which 70 is threaded on the bolt 22 and which forms a means for adjusting said bolt and the attached form plates. The nut is preferably a split nut and comprises a pair of symmetrical sections 30 and 30^a which are provided 75 with hinge eyes 31 connected by a suitable pintle 32. One of the members is provided with a swinging bolt 33 pivoted to a lug 34, which bolt extends through slots 35 in both lugs 36, the pin being provided with a 80 wing nut 37 whereby the two nut sections may be clamped together to form an operative or complete nut. Each section is provided with a socket 38 which is adapted to receive a bar, or similar operating means, 85 for rotating the nut. Coöperating with the hooks 23 and 29 is a chain 39.

In the drawings I have shown six points of connection between the form or mold and the elevation devices, with three tie members 90 18 extending diametrically across the form and connecting opposed posts or ribs. These tie members are shown as extending continuously across and above the top of the form, being so arranged as to just clear each other 95 at the axis of the form. This arrangement, however, is not essential, as it will be evident to those skilled in the art that the cross ties may all be arranged in a substantially common horizontal plane, as by 100 having their inner ends socketed into arms of a central spider.

With the parts arranged as illustrated and described, it is believed that the operation will be easily understood. The grouting is placed between the inner and outer walls of the mold or form by the workmen. The form will be elevated substantially continuously by a workman detailed to operate the nuts. The chains 39 which connect the 105 hooks 23 and 29 are particularly efficient in this operation. For instance, when one of the bolts 22 has been elevated substantially as far as possible or convenient, the mold or form being meanwhile supported by the 110 other hooks and chains, the nuts for the particular pair of bolts 22 may be opened, the bolts dropped to their lower limit and the nuts re-applied to said bolts; the slack of the chain will then be taken in and the 115 operation of elevating the form may then be resumed. With this arrangement, it will be evident that the mold or form may be elevated a number of times before the upper and lower hooks will be brought into substantial engagement and hence before it will be necessary to shift upwardly the tie members 18 and the supporting members 19. 120

It will be noted that, in elevating the inner and outer form plates, I make use 130

in such elevation of form members (in this case, posts) which constitute a supporting means for the molded wall throughout the entire molding operation; also that these 5 supporting members for the molded wall extend continuously from the top to the bottom thereof and are in engagement with such wall; also that the construction employed makes it possible to increase (by 10 addition to the top) the length of said posts or members whereby they may be used for the purpose of elevating the mold plates irrespective of the height of the wall which is to be molded.

15 The construction described herein, while extremely efficient, is correspondingly simple in construction and economical of production and application. For convenience of description, the members B and C will be 20 referred to as "plates" in the claims hereto annexed, it being understood that by the use of this expression I do not thereby limit my invention to the use of any particular material which may be employed in the production of such members. The outer wall 25 of the mold is, in effect a continuous plate composed of a plurality of individual plates connected at their lateral edges.

Having thus described my invention, 30 what I claim is:

1. The combination, with a form comprising an outer series of plates connected at their lateral edges and an inner series of plates connected to each other and to the 35 outer plates with their lateral edges spaced, posts along which the lateral edges of the inner plates are adapted to move, and means carried by the posts for moving both series of plates longitudinally with respect to said 40 posts.

2. The combination, with a form comprising a series of plates connected at their lateral edges and a series of plates transversely spaced from the plates of the first series and 45 having their lateral edges spaced, connections between the plates of both series whereby these series are connected and maintained in transversely-spaced relation, posts 50 cooperating with the spaced lateral edges of one series of plates, and means carried by said posts and adapted to engage said connections thereby to move both series of plates longitudinally with respect to said posts.

55 3. The combination, with a pair of opposed posts, of an outer mold wall extending between said posts, an inner mold wall connected to the outer mold wall and transversely spaced therefrom and adapted to engage the lateral sides of said posts with its opposite lateral edges, means carried by 60 each of said posts for moving the mold walls therealong, and a brace connecting said posts.

65 4. The combination, with a form comprising

ing an outer series of connected plates and an inner series of plates transversely spaced from the plates of the outer series, posts adapted and arranged to be engaged by the plates of the inner series, means connecting 70 the plates of the inner series with the plates of the outer series, and means carried by the posts for moving the plates of both series therealong.

5. The combination, with a post, of a pair 75 of transversely spaced connected mold plates, the lateral edge of one of said plates having a sliding engagement with a side of said post, and means carried by said post for moving the plates simultaneously therealong.

6. The combination, with a post, of a pair 80 of transversely spaced mold plates movable therealong, means connecting and spacing said plates, and means for moving said 85 plates along said post, said means comprising a threaded bolt supported by said post, connections between said bolt and such connecting and spacing means, and a nut on said bolt operatively supported from said post. 90

7. The combination, with a pair of transversely spaced mold plates, of a post along which one of said plates is adapted to be moved, said post and one of said plates having an interengaging sliding connection, 95 means connecting and spacing said plates, and means carried by said post for moving said plates therealong, said means comprising an apertured support carried by the post, a threaded bolt extending loosely 100 through such aperture, a nut on said bolt adapted to engage said support, and means connecting said plates to said bolt.

8. The combination, with a pair of transversely spaced mold plates, of a post along 105 which one of said plates is adapted to be moved, said post and one of said plates having an interengaging sliding connection, means connecting and spacing said plates, 110 and means carried by said post for moving said plates therealong, said means comprising an apertured support carried by the post, a threaded bolt extending loosely through such aperture and having a hook, 115 a nut on said bolt adapted to engage said support, and a chain operatively connected to said plates and to said hook.

9. The combination, with a pair of transversely spaced plates, of a post along which one of said plates is adapted to be moved, 120 said post and one of said plates having an interengaging sliding connection, a supporting member detachably connected to said post, said member having an aperture, a threaded bolt extending through said aperture, a nut on said bolt and bearing against said member, said bolt having a hook, and a chain connecting said hook to said plates. 125

10. The combination, with a pair of transversely spaced plates, of a post along which 130

- one of said plates is adapted to be moved, said post and one of said plates having an interengaging sliding connection, a supporting member detachably connected to said post, said member having a sleeve, a threaded bolt extending through said sleeve, a nut on said bolt and bearing against said sleeve, said bolt having a hook, and a chain connecting said hook to said plates.
10. 11. The combination, with an outer mold plate, of a pair of inner mold plates, a post adapted to engage the adjacent edges of such inner plates, means connecting the inner plates with the outer plates, a reciprocable device carried by the post, and means connecting said device with said plates whereby they may be moved in unison along said post.
12. The combination, with a form comprising a pair of opposed posts, of a series of connected outer plates extending outside of and inclosing said posts, a series of inner plates adapted to engage said posts with their lateral edges, means carried by each of said posts for moving the inner and outer series of plates therealong, and a tie member connecting said posts.
13. The combination, with a form comprising a pair of opposed posts, of two spaced series of connected plates adjustable along said posts, means carried by each of said posts for moving the series of plates therealong, and a tie member connecting said posts.
14. The combination, with a form comprising a pair of opposed posts, of a series of connected outer plates extending outside of and inclosing said posts, a series of inner plates adapted to engage said posts with their lateral edges, means carried by each of said posts for moving the inner and outer series of plates therealong, said means comprising a supporting member connected to each of said posts, a tie member connected to said supporting members, and means carried by each of the supporting members and connected to the inner and outer series of plates for moving the same along said posts.
15. The combination, with an outer series of connected plates arranged to provide an enclosure, of a series of inner plates spaced from the outer plates, posts extending between the plates of the inner series and adapted to be engaged by the edges of said plates, tie members connecting opposed posts, and means carried by said posts for moving the inner and outer series of plates therealong.
16. The combination, with a movable form plate, of a rib or post associated there-
- with, and means carried by said rib or post for moving said plate with respect thereto, said means comprising an apertured member carried by the post, a threaded rod extending loosely through such member, means connecting said rod to said plate, and a split nut on said rod and operatively engaging said member, said nut having one or more sockets for the application of a lever or levers thereto.
17. The combination, with a movable form plate, of a rib or post associated therewith, and means carried by said rib or post for moving said plate with respect thereto, said means comprising an apertured member carried by the post, a threaded rod extending through said member, means connecting said rod to said plate, and a split nut on said rod and operatively engaging said member.
18. The combination, with a post, of a pair of inner plates adapted to coöperate with the sides of said post and movable therealong, one or more outer plates complementary to the inner plates, a yoke connecting and spacing said plates, and means carried by the post and connected to said yoke for moving said plates along the post.
19. The combination, with a post, of a pair of plates adapted to coöperate with the sides of said post and movable therealong, another pair of plates complementary to the first mentioned pair, a yoke connecting and spacing said plates, a hook projecting from said yoke, and means carried by the post and coöperating with said hook for moving said plates along said post.
20. The combination, with a form comprising a plurality of posts adapted and arranged to engage one of the sides of the wall molded by such form, of transversely spaced plates extending between said posts, means connecting and spacing said plates, and means connected with said posts and said plates for moving the plates longitudinally of the posts.
21. The combination, with a form comprising a plurality of posts adapted to engage and support the article to be molded, of plates interposed between said posts and adapted to be moved therealong and coöperating with said posts to support such article, of other plates transversely spaced from the last mentioned plates, and means connected with said posts for moving both sets of plates simultaneously therealong.

In testimony whereof, I hereunto affix my signature.

HARRY O. DAVIDSON.
